WOVEN BELT CONSTRUCTIONS

Robert L. White, Claremont, Calif.

Application October 3, 1955, Serial No. 538,123

4 Claims. (Cl. 139—425)

This invention relates to new and improved woven belt or strap constructions; more particularly, it relates to wire belts or straps having uniquely advantageous woven constructions.

An object of this invention is to provide new and improved woven belt or strap constructions utilizing wires of the type which may be termed "plastic coated electrical wires." A related further object of the invention is to teach the construction of belts or straps of this category which may be used for a wide variety of different purposes, and, hence, which may be termed "universal" in character.

A distinguishing feature of this invention lies in the use of a particular category of wire. At the present time, electrical wires are used for a wide variety of purposes, such as telephone installations, which wires are formed utilizing a core of either a solid strand of wire or plurality of strands of wire twisted together. The cores are coated with a comparatively thin adherent coating of a plastic material. The properties of this plastic material are very important for electrical purposes; these same properties particularly adapt these electrical wires for use in woven belts or straps of this invention.

The strength of the construction of belts or straps according to the present invention is primarily derived from the inherent strength of the wire cores. Suitable metals for such cores are copper, aluminum or the like. The coatings placed upon the cores may be virtually any common, flexible, water-resistant, durable, heat and abrasion resistant material, such as compositions based upon the use of polyvinyl chloride, polyvinyl acetate, polyethylene, nylon, polyurethanes, or other related resins and copolymers. Obviously, such compositions can, and normally do, contain various amounts of plasticizers, fillers, pigments, and the like. These coatings are normally applied to a wire core by various extrusion processes, although they may be also applied by various dipping procedures.

Regardless of the method of application employed, such coatings serve to protect the wire core utilized from corrosion. These coatings also serve to present a pleasing appearance to the eye since they may be colored in any desired manner. Thus, the belt or strap constructions of the invention can be distinguished from prior constructions since they can be formed to have a pleasing appearance involving a number of different colors. Their appearance is not, however, limited to the use of any particular combination of colored wires; any belt or strap of the invention, regardless of color, is considered to be ornamental from a design viewpoint.

Hence, it may be considered that an object of the present invention is to provide a new and ornamental design for a woven belt or strap or the like. Further objects of this invention, as well as many specific advantages of it will be more fully apparent from the remainder of this description, including the appended claims and the accompanying drawings in which:

Fig. 1 is a top view of a woven belt formed in accordance with this invention, illustrating the design of such a belt;

2

Fig. 2 is a side view of the belt shown in Fig. 1; Fig. 3 is a top view illustrating how a belt retainer may be located on a belt such as is shown in Fig. 1; and Fig. 4 is a side view of the structure shown in Fig. 3.

5 In all figures of the drawing like numerals are used to designate like parts wherever convenient for purposes of illustration and explanation. Although the constructions shown on the drawing represent preferred, actual embodiments of the invention, it is to be understood that other structures falling within the scope of this invention may be created without departing from the essential features herein described.

10 In order that the present invention may be completely understood, the concept behind the invention may be briefly summarized as being concerned with a belt or strap construction which involves first and second woof wires located in a manner such that they may be considered to be positioned one over the other, said first and said second woof wires being bent so as to each include loops formed thereon; and first and second warp wires positioned generally parallel to one another, each of said warp wires passing over and under portions of said woof wires forming said loops, in order to form a unitary woven or braided belt or strap.

15 Obviously, a summary of this nature is not sufficient to completely indicate to those skilled in the art to which this invention pertains the exact nature of the invention. For this reason, reference is made to the accompanying drawing and in particular, to Figs. 1 and 2, where there

20 is shown a part of the belt 10 of the present invention which is intended to be worn by an individual. This belt 10 is formed so as to include a common belt buckle 12 having a base 14 and a belt tongue 16 attached to this base so as to be pivotally mounted with respect to it.

25 Attached to the base 14 on each side of the tongue 16 are first and second warp wires 18 and 20. On each side of these two warp wires there are attached to the base 14 first and second woof wires 22 and 24. While a number of different means may be used to attach these wires to the base 14, it is preferred with the instant invention to utilize a common girth hitch. The use of a knot of this

30 category has the result that all of the individual wires composing the belt 10 are, in fact, double, inasmuch as the warp wires 18 and 20 and the woof wires 22 and 24 are each composed of two separate strands or wires located side by side in substantially a single plane. This

35 is quite advantageous with the instant invention inasmuch as when two separate wires are used for each of the warp and woof strands or wires of the belt 10, the angles at which these wires are bent in the belt are increased, or stated in another way, the radii of curvature of the various individual strands in these wires in the final belt is increased. The larger such radii, the easier it is to form the belt 10, and also, the less danger of the wire cores

40 within the wires used breaking.

45 50 55 In forming the belt 10, the various warp and woof wires are located with respect to one another so as to project from the base 14 of the buckle 12. Next, the wire 22 is passed under the warp wires 18 and 20 so as to form a loop 26. The woof wire 24 is then passed under the top end of this loop 26, over the warp wire 20, under part of the loop 26, over the warp wire 18, and then under the woof wire 22 adjacent to the base 14.

60 The woof wire 24 is then bent to form and loop 28 and passed over the warp wires 18 and 20 so as to form another loop 26 immediately adjacent to where it was previously passed through the loop adjacent to the warp wire 20. Also, the woof wire 24 is passed under the portion of the woof wire 22 between the warp wires 18 and 20. When this operation has been carried out, the entire

65 70 process is repeated a number of times so as to form the complete belt 10.

Those skilled in the art to which this invention pertains will realize from a consideration of the foregoing together with the accompanying drawings, that each of the warp wires 22 and 24 are, in essence, located in the belt 10 so as to have a series of loops formed therein, these loops facing opposite directions and being formed so that the side of one loop forms part of the next adjacent loop. It will also be realized that the first and second warp wires 24 and 22 are respectively located generally above and below the warp wires 18 and 20 with the loops formed on the roof wires 22 and 24 being offset with respect to one another by an amount equal to approximately half of the width of any one loop. It is considered obvious that the various individual loops employed are of substantially the same or equal dimension.

It is readily seen in Fig. 1 of the drawings that the first warp wire 18 is located so as to project over alternate loops formed on the first warp wire 22, and so as to project under portions of the second warp wire 24 located generally beneath these alternate loops on the first warp wire. The second warp wire 20 is similarly located so as to project over the other remaining alternate loops on the first warp wire 22 and under the portions of the second warp wire 24 located generally beneath these other alternate loops in the first warp wire 22. This type of structure is quite advantageous inasmuch as the warp and woof wires are in essence woven or interlaced together in a comparatively simple manner in which the wires are securely held, and in which the wires are capable of a certain amount of "give" or adjustment during use. The ends of the wires in the belt 10 may be conveniently secured together once a desired length has been reached by any desired method, such as embedding, all the ends of these wires in a solid block of a plastic, or by soldering or otherwise attaching these ends to one another.

If desired, the belt 10 may be modified as shown in Figs. 3 and 4 of the drawings so as to include a belt retainer 30, having a base 32. This base 32 is adapted to be held beneath the warp wires 18 and 20 generally above the warp wires 22 and 24. This retainer may be easily and conveniently placed within the belt 10 during weaving or braiding of this belt.

While the preferred embodiment of the invention involves a belt for use by an individual, it is to be understood that the invention is not limited to belts or straps for such applications, although the invention is particularly adapted for such use since belts constructed as herein described easily conform to various bodily contours, and do not take a permanent set. Also, because of the essentially open nature of the belt 10, this belt provides excellent ventilation and is comparatively cool to wear. Because of the inherent nature of the weave, a number of openings are, in essence, left between the warp wires 18 and 20 and between the warp wires 22 and 24, so that the tongue 16 may be inserted in the belt 10 at any location in order to secure this belt.

One major advantage of the instant invention lies in the fact that belts or straps as herein described can be easily cleaned by the use of conventional detergents and water, without damage because of the nature of the plastic coatings utilized. These plastic coatings are also extremely advantageous when belts as herein described are used in industrial applications, such as motor belts, where a corrosive atmosphere is present. The plastic coatings in such applications prevent the wire cores used from being attacked by corrosive elements present. The belts or straps of this invention are also advantageous when used on pulleys and the like because of the inherent tendency of the weave and plastic to exert a considerable amount of traction.

Those skilled in the art to which this invention pertains will realize that a number of minor modifications may be made in the structure shown without departing

from the essential nature of this invention. As an example of such modifications, only a single strand of wire may be used for each of the warp wires employed, although this is not preferred inasmuch as it is believed that this will detract from the essential design appearance of the product created. The appearance of belts or straps as indicated in the drawing is considered to be quite important from an esthetic point of view. Belts or straps as herein defined can be made continuous by various obvious expedients.

Those skilled in the art will further realize that belts or straps as herein described are very economical to manufacture and that these belts or straps can be woven out of wires having different colors so as to present varying appearances. Because of these considerations, the invention is to be accorded comparatively wide latitude, and is to be considered only as being limited by the appended claims forming a part of this disclosure.

I claim:

1. A new and improved belt of the class described which comprises: first and second warp wires located one above the other, each of said wires being bent so as to include loops facing alternate directions, said loops on said wires being of approximately equal dimensions, and said loops on said second warp wire being offset with respect to said loops on said first wire; and first and second warp wires engaging said warp wires so as to pass over parts of said loops formed on said first warp wires and parts of said loops formed on said second warp wires.

2. A new and improved belt which comprises: first and second parallel warp wires spaced from one another; and first and second warp wires interlaced on said warp wires whereby said first warp wire forms a series of loops beneath said warp wires and said second warp wires form a series of loops above said warp wires, said loops on one side of said warp wires being offset with respect to the loops on the other side of said warp wires, said loops formed on said first and second warp wires being held together by said warp wires so as to form a flat, unitary belt.

3. A new and improved belt which comprises: a first warp wire having a series of loops formed thereon so that the alternate loops on said first warp wire face opposite directions; a second warp wire having a series of loops formed thereon so that the alternate loops on said second warp wire have substantially the same dimension as said loops in said warp wire, said loops on said second warp wire being offset with respect to said loops in said first warp wire approximately half the width of said loops; a first warp wire located so as to project over alternate loops on said first warp wire and under the portions of said second warp wire generally beneath said alternate loops on said first warp wire; and a second warp wire located so as to project over said other alternate loops on said first warp wire and under the portions of said second warp wire generally beneath said other alternate loops on said first warp wire.

4. A belt which comprises: a buckle structure having a base formed thereon; first and second warp wires attached to said base adjacent to the center of said base by girth hitches, said warp wires being generally parallel to one another and being spaced from one another; first and second warp wires attached to said base by girth hitches at the sides of said first and said second warp wires, said first and said second warp wires projecting from said base so as to be located generally one above another, and said first and said second warp wires being bent so as to include loops formed thereon, said loops being held together by said warp wires passing over and under portions of said warp wires forming said loops.
